UNITED STATES PATENT OFFICE.

JOHN G. LYON, OF PITTSBURG, PENNSYLVANIA.

DESIGN FOR GLASSWARE.

SPECIFICATION forming part of Design No. 20,411, dated December 16, 1890.

Application filed September 30, 1890. Serial No. 366,689. Term of patent 3½ years.

To all whom it may concern:

Be it known that I, JOHN G. LYON, a resident of Pittsburgh, in the county of Allegheny and State of Pennsylvania, have invented a new and original Design for Glassware; and I do hereby declare the following to be a full, clear, and exact description thereof, reference being had to the accompanying drawings, in which—

10 Figure 1 is a side view of a jug illustrating my design. Fig. 2 is a top view of the same; and Fig. 3 is a cross-section on the line 3 3, Fig. 1.

Like letters of reference indicate like parts 15 in each.

The leading feature of my design consists in a body for jugs, bottles, inkstands, or like articles of glassware bulbous in shape and having a series of deep vertical V-shaped 20 grooves extending into the same.

The body *a* of the jug or other article is bulbous or ball-like in shape, and formed around the same are a series of deep vertical V-shaped grooves *b*, the sides *c* of said grooves 25 being substantially flat and meeting in a slightly-curved base-line *d*, the curve of the base-line being much flatter, however, than the curve of the outer lines *e* of the grooves *b*. As so formed the faces of the bulbous body 30 between the grooves are therefore formed on a curve corresponding to the bulbous body

and are wider at the top and bottom portions, as at *f* and *g*, than in the central portion *i* thereof.

The glass article may be formed with a 35 neck, such as for jugs, bottles, &c., or without a neck, such as for inkstands; but such neck forms no essential part of my design. Where the glass article has a neck I prefer that illustrated in the drawings, in which the 40 neck *h* of the jug or other article extends up from the bulbous body and is formed with substantially vertical walls having a series of flat vertical faces *k* around the same, which meet to form the angles *m*, and the outer wall 45 of the neck portion is therefore made up of a series of angles *m* and flat faces *k*. In jugs and some class of bottles I provide the article with a handle, as at *n*.

What I claim as my design, and desire to 50 secure by Letters Patent, is—

The design for glassware herein shown and described, consisting in a bulbous body having a series of deep vertical V-shaped grooves extending into the same, as set forth. 55

In testimony whereof I, the said JOHN G. LYON, have hereunto set my hand.

JNO. G. LYON.
